UNITED STATES PATENT OFFICE

EDWARD E. KLEINSCHMIDT, OF CHICAGO, ILLINOIS, ASSIGNOR, BY MESNE ASSIGNMENTS, TO TELETYPESETTER CORPORATION, OF CHICAGO, ILLINOIS, A CORPORATION OF DELAWARE

SELECTING TELEGRAPH

Application filed April 14, 1928. Serial No. 269,883.

The invention relates to selecting telegraphs and seeks to provide an improved system and apparatus for rapidly effecting the transmission from one station and the recording at a distant station of code signals such as required for effecting the operation of a type-setting or casting machine, and particularly a monotype machine that is controlled by a record strip or tape perforated in accordance both with character signals, representing letters, numbers and punctuation marks, and also justification signals.

Further objects of the invention are to provide an improved transmitter adapted to be controlled by a perforated record strip such as is now used with a monotype machine and an improved receiver or recording perforator producing such a record strip, and also an improved code and system for use in connection with such apparatus.

In the monotype system, the character signals are made up of thirty components. Each signal comprises two components, one selected from one group of fifteen and the other from another group of fifteen and these signals are represented on the tape by transverse rows of holes. There are two holes in each transverse row, each of which occupies any one of a group of fifteen possible punch positions disposed on opposite sides of the center of the tape and which may be designated for convenience, the A and B groups. Certain justification signals include an additional third component represented by a hole in a sixteenth position on the B side of the record strip.

In accordance with the present invention the transmitting and receiving selectors which determine the signals sent and recorded respectively are divided into A and B groups and separate sets of permutation members of four each are provided, one set for each group of selectors and such members are adapted to be conditioned in different combinations to represent the two elements or components of the signals. Also, an 8-unit code consisting of permutations of two different electrical conditions extending through eight successive time intervals or units is utilized, each signal being divided into two sets of four units

in correspondence with the separate sets of permutation members and the two components of the different signals. Provision is thus made for sending and recording the large number of different signals required with a comparatively short code. Means are also provided for transmitting and recording the special three component justification signals without increasing the lengths of the other signals.

The improved transmitter and receiver employed are provided with motor driven distributors which are maintained in proper phase relation by starting and stopping intervals or units which are transmitted by the sending distributor in advance of and following each code signal and which serve to initiate and arrest the receiving distributor at the beginning and end respectively of each signal period.

The foregoing and other features of the invention as hereinafter more fully set forth, are illustrated in the preferred form and arrangement in the accompanying drawings and more particularly pointed out in the appended claims.

In the drawings,

Fig. 1 is a diagrammatic representation of the improved system and apparatus.

Figs. 2 and 3 are plan and side views with parts shown in section of the improved transmitter.

Figs. 4, 5, and 6 are detailed views of the transmitter selectors.

Figs. 7, 8, 9, and 10 are detailed views of the feed mechanism for the transmitter controlling tape.

Figs. 11, 12 and 13 are plan, vertical sections, and side views respectively, and

Fig. 14 is a horizontal section of the improved receiver or perforating recorder.

Figs. 15 and 16 are detailed views of the receiver selector mechanism.

Figs. 17, 18, 19 and 20 are detailed views illustrating the operation of the receiver recording and perforating devices and of the feed mechanism for the record strip or tape formed thereby.

The transmitter is preferably controlled by a perforated tape or strip 10, prepared by a

regular monotype keyboard perforator. This strip has longitudinal rows of feed holes at its opposite edges and is advanced step by step through a guide 11 to bring its transverse rows of signal holes over a series of transmitter selectors in the form of vertically disposed tape pins 12. The reduced ends of the pins extend into openings in the tape guide 11 and in a lower guide bar 13 and an additional guide bar 14 holds the pins against turning.

Individual springs 15 tend to lift the pins through the perforations of the tape when a common transverse resetting bar or bale 16 is lifted. The latter is mounted on a horizontal shaft 17 and is operated by a cam 18 on a main transmitter shaft 19.

The tape is advanced step by step by feed wheels 20 arranged below the path of the tape on a horizontal shaft 21 and the latter is actuated from a cam 22 on the main shaft 19 through the medium of a feed lever 23 provided with a pawl 24 engaging a ratchet 25 on the feed shaft.

At the end of each signal the cams 18 and 22 operate the resetting bale 16 and the feed lever 23 to depress the tape pins that have been lifted, advance the tape to bring the next transverse row of signal holes over the pins, and then permit the lifting movement of the corresponding pins.

As stated, the tape has two holes in each transverse row disposed on opposite sides of the center thereof, there being fifteen possible positions on the tape for each of such holes. The tape pins are correspondingly divided into A and B groups and one pin of each group is lifted at each operation. There is also a third perforation in the transverse rows representing certain justification signals which permits the lifting of an additional tape pin 12' in the B group.

Separate sets of permutation members 26a and 26b are associated respectively with the two groups of tape pins and each set of four members is adapted to be conditioned by the group of tape pins associated therewith in a corresponding number of different combinations. In the form shown, each set of permutation members comprises four plates or bars arranged one above the other and pivoted to swing on horizontal axes. The permutation bars or members are spring-held in normal position and the tape pins are provided with code lugs 27 for shifting the members in different combinations when the pins are lifted. The transmitter shown is provided with a sunflower distributor and the permutation members 26 are provided with a contact 28 movable therewith and each arranged between front and back contacts.

The distributor comprises a brush 29 mounted on the end of the transmitter shaft 19 and arranged to successively connect a series of segmental contacts with a ring con-

tact 30 and the main line conductor 31 which extends through a line relay 32 (see Fig. 1) at the receiving station.

The main transmitter shaft 19 is driven from a continuously operating motor 33 through gearing 34 and a friction clutch 35. A stop-start device in the form of an armature lever 36 cooperates with a stop disk 37 and, when engaged therewith, holds the transmitter shaft at rest with the brush engaging the stop segment 38. The stop and start segments 38 and 39 are connected to the opposite poles of a divided line battery 40 and the segmental contacts 1 to 4 inclusive on the A side of the distributor and 5 to 8 inclusive on the B side are variably connected to the line battery by the corresponding sets of permutation members 26a and 26b.

As shown, the segments 1 to 6 inclusive are connected directly to the corresponding permutation switches and the front and back contacts of the latter are connected to the opposite poles of the line battery. The segments 7 and 8, which affect the transmission of the last two units or intervals of each code signal,

may be similarly connected to battery by the corresponding switches, but preferably they are connected to armature levers 41 having front and back battery contacts and operated by relays 42 which in turn are connected to the corresponding permutation switches. Relays 42 are provided with armature levers 43 which control a locking circuit for the relays from a local battery. This locking circuit is opened when the distributor brush 29 reaches or passes through its rest position by a cam 44 on the shaft 19 and which operates a releasing switch 45. Each revolution of the transmitting distributor from and back to its rest position, effects the transmission of a signal comprising two 4-unit permutations of positive and negative impulses (or so-called "marking" and "spacing" pulses) in accordance with the setting of the groups of permutation members 26a and 26b, each signal being preceded and followed respectively by uniform starting and stopping impulses of different polarity.

The relays 41 which store the last two marking pulses afford ample time for the restoring and resetting of the permutation members during the latter portion of each signal period and before the transmission of the first selecting unit of the succeeding signal. Obviously, if desired, the signals may consist of permutations of current and no-current units or intervals.

The special tape pin 12' does not position the permutation switches. Instead, when it is operated by a third or additional hole in a row of perforations of the tape, it lifts a bell crank lever 46 which normally engages a shoulder on the hub of a gear 47. The latter is mounted on a short shaft 48 which is driven, when the trip lever 46 is released by the special tape pin 12', from the main shaft

19 by a friction clutch 49 and a gear 50. The shaft 48 carries a cam 51 which operates a bell crank lever 52 and the latter serves to disable or prevent the feeding operation of the tape feed lever 23 and also serves when shifted to engage a pair of normally open contacts 53. The latter as shown in Fig. 1, are interposed in the energizing circuit of a relay 54 which is arranged to disconnect the main line conductor from the distributor contacts and connect it directly to the marking side of the line battery. The cam 51, which is driven at half the speed of the main transmitter shaft by the two-to-one gears 47 and 50, holds the cut-out lever 52 in shifted position only during the second half of its revolution. Hence, during the first half of the revolution of the cam, two 4-unit permutations are transmitted as described under control of the two other tape pins which rise with the special tape pin 12'. But at the end of such signal, cut-out lever 52 is shifted to prevent the feed of the controlling tape and connect the line to the operating or marking side of the battery during the succeeding revolution of the distributor and a code signal consisting of all marking units or intervals is transmitted. At the end of this signal, the lever 52 is returned to normal to permit the operation of the tape feed lever and again connect the line to the distributor contacts.

The recording receiver has a continuously operating motor 55 which drives a distributor shaft 56 and an operating shaft 57 (see Figs. 12 and 14) through the medium of sets of gears 58 and friction clutches 59. Start-stop levers 60 cooperate with shouldered disks 61 on these shafts and are controlled by magnets 62 and 63 respectively so that each shaft rotates through a single revolution when the corresponding start magnet is operated. A distributor brush 64 on shaft 56 is arranged to bridge a series of segments and a ring 65 which is connected to the front contact of the line relay 32. The tongue of the line relay is arranged to connect a local battery 66 to its front contact upon the receipt of marking or operating signal units or intervals.

Magnet 62 is connected to segment 67 which is engaged in the normal or rest position of the brush 64 so that the latter is initiated in operation by the starting unit of each signal and successively engages the segments 1 to 8 inclusive during the corresponding permutation or selecting intervals of the signal. Thereby, the variable operation of a series of selecting magnets 68 which are connected one to each of these segments is effected and control the setting of two sets of permutation members 69a and 69b in different combinations in accordance with the two 4-unit permutations of each of the signals.

Each set of permutation members preferably comprises four notched bars, each longitudinally movable to either one of two posi-

tions to selectively align their notches in a well-known manner. Preferably, the permutation bars are held in normal position against the tension of shifting springs by latches 70 that are tripped by the selecting magnets 68. Restoring shift levers 71 operated by cams 71a and 71b on shaft 57, are provided for re-engaging the bars with the latches at the ends of the operation of each set. The alignment of the notches of the permutation bars determines the operative setting of one each of two groups of punch selectors 72a and 72b during each signal period. These selectors, in the form shown, are disposed in horizontal position above the permutation bars and the operating shafts and are pivotally connected at their rear ends to the upper ends of a set of levers 72. The latter are pivotally mounted at their lower ends and are spring pressed toward the notched edges of the permutation bars. Normally the selectors are held in retracted position and out of engagement with the permutation bars by two shifter bars or bales 73 mounted on a pivoted shaft 74 and have arms 75 operated by the cams 73a and 73b on shaft 57.

The forward ends of the selectors extend through a guide plate 76 and when advanced are interposed between the lower ends of two corresponding groups of punches 77 and two punch actuating bars or bales 78. The punches are mounted in a block 79 which, together with an upper die block 80, forms a guide for a recording strip or tape 81. The punch actuators are operated by cams 78a and 78b on the shaft 57.

Magnet 63 which controls the operating shaft 57 is operated by a brush 82 which bridges contacts 83 interposed in its energizing circuit at the end of a half revolution of the distributor or at the end of the setting of the permutation bars 69a. The cams 73a, 78a, and 71a then operate the shifting, punch actuating, and restoring bars 73, 78 and 71 of the A side of the recorder and effects the operation of a selected punch in the A group. Also, since the cams 73b, 78b, and 71b are disposed 180 degrees behind those of the A side, they similarly effect the operation of one of the B punches after the setting of the permutation bars 69b. Thus, the selecting and operating cycles for the two groups of recorders or punches overlap; that is to say, the selection of one of the B punches is effected during the operation of the selected recorder or punch of the A group, and the selection of an A recorder can be effected by the initial 4-unit permutation of the succeeding signal during the operation of the B recorder selected by the preceding signal. It is only necessary that the operating shaft 57 shall complete the operation of both sides of the recorder in response to any signal before its controlling magnet is energized dur-

ing the mid-portion of the succeeding signal. The record tape or strip 81 is advanced upon the return stroke of the B punch actuator 79 by means of a spring pressed dog 84 mounted on the B punch actuator and arranged to engage a pin on the operating lever 85 of a pawl and ratchet feed mechanism. No feeding movement of the tape however, is effected upon the operation of one of the A punches so that the holes successively formed by the A and B punches selected by each signal, are aligned in a single transverse row across the tape.

The transmission of special three component justification signals is effected as described during two successive rotations of the distributors, the first rotation serving to select and effect the operation of one of the A and then one of the B punches, and then advance the record strip one step. During the succeeding rotation of the distributors, the transmitting distributor is disconnected from the line as described and the latter is so controlled by the magnet 54 that the tongue of the line relay is maintained against its front contact so that all of the selecting magnets are operated. The resulting setting of the A and B permutation bars effects the selection only of the special punch controller or selector 72' of the B group and which is arranged to effect the operation of a special punch 77'. The latter is forwardly offset as indicated in Fig. 11 so that the hole punched thereby aligns with the previously formed A and B holes of the special justification signal.

The selector 72' is also provided at its end with a projecting pin 86 which is arranged to disable or prevent the operation of the dog 84 by engaging it and shifting it as shown in Fig. 20 so that there is no feeding operation of the record strip after the operation of the special punch. The arrangement described permits the transmission and recording of special three component signals without increasing the lengths of the periods required to send and record most of the signals which consist of two components only.

As usual in start-stop telegraph systems, the operating motors are governor controlled to maintain uniform speeds of the respective sending and receiving distributors. Preferably the stop arm 76 of the sending distributor is held in operative position by a normally energized magnet 87, so that the sending distributor operates continuously and is not arrested in its normal position unless the circuit of the magnet 87 is opened by a switch 88. The latter can be operated manually to start and stop the sending of signals and also by a loop of the transmitter controlling tape 10 to prevent breaking of the tape as it is delivered to the automatic transmitter from a keyboard perforator. Preferably also, to insure the stop of the receiving distributor at the end of each signal and its starting in

place with the succeeding signal, it is driven at a speed slightly faster than that of the sending distributor.

The invention provides an improved system or method of sending and recording signals in accordance with a code comprising thirty elements or components for the character signals, with an additional element for justification, by means of a relatively shorter code comprising only eight elements, or ten, if the preferred start-stop system is employed. It is also noted that each complete transmitted signal is compound and in effect comprises two separate signals or code combinations, one for each component of the original code.

The improved transmitter and recording perforator are simple and compact, the parts being mounted on base boards 89 between side brackets 90 and below the paths of the tapes. But numerous changes may be made without departure from the scope of the appended claims.

I claim as my invention:

1. In a telegraph system, the method of sending and recording signals each consisting of one of each of a plurality of groups of components, which comprises successively transmitting, during each signal period, a plurality of definite interval permutations of two different electric conditions, one permutation for each component of the corresponding signal and separately selecting and recording the individual components of each signal in response to said permutations.

2. In a telegraph system, the method of sending and recording signals normally comprising two components and special code signals comprising three components, which consists in transmitting two definite interval permutations of two different electrical conditions during each normal signal period and a certain definite signal during each of a number of special signal periods of normal lengths, and selecting and effecting the operation of one each of two groups of recording devices in response to the permutations of each normal signal period and of a special recording device in response to each of said definite signals.

3. In a telegraph system for reproducing a perforated record strip having two groups of possible hole positions extending transversely of the strip and transverse rows of holes each having one hole in each of such groups and certain special rows having an additional third hole in a definite position, means for transmitting, under control of the tape, two definite interval code permutations during each normal signal period and a definite signal during each of a number of special signal periods, and a receiving perforator having two groups of punches and a special punch and two sets of permutation members for selectively controlling the operation of

- one punch in each group in response to the corresponding permutations of each signal, one set of permutation members being operative in response to the special signals to effect the operation of the special punch. 5
4. In a telegraph receiver, a plurality of recording devices, divided into groups, selecting and actuating means individual to each group, a common record feed mechanism, and 10 means responsive to received signals for effecting the operation of the selecting and actuating means of the respective groups and said feed mechanism in successive predetermined order. 15
5. In a telegraph receiver, a plurality of recording devices divided into groups, a set of selectors and an actuator individual to each group of recording devices, a common record feeding means, and means, responsive to received signals and including a common operating mechanism for said actuators and said feeding means, for successively operating the selectors and actuators of the different groups of recording devices and for finally 20 operating the record feed mechanism. 25
6. In a telegraph receiver, a plurality of recording devices divided into groups, a set of selectors and an actuator individual to each group of recording devices, a common record feed mechanism, a common distributer and associated electro-magnetic means for successively conditioning said sets of selectors in different combinations, and means controlled in operation by said distributer for 30 successively operating said actuators and for finally operating said common record feed mechanism. 35
7. A recording perforator comprising two groups of punches and corresponding punch 40 selectors, a separate set of controlling permutation members and a punch actuator for each group, a distributer and electro magnetic means responsive to received definite interval code permutations for successively conditioning the set of permutation members in 45 different combinations, and means controlled by said actuator for effecting the operation of the selected punch of each group during the selection of the punch of the other group. 50
8. A recording perforator comprising two groups of punches and corresponding punch 55 selectors, a separate set of controlling permutation members and a punch actuator for each group, a distributer and electro magnetic means responsive to received definite interval 60 code permutations for successively conditioning the sets of permutation members in different combinations to select one punch in each group in response to each received signal, and means initiated in operation by said distributer for successively operating said actuators and arranged to effect the overlapping of the selecting and operating cycles of the two groups. 65
9. In a recording strip perforator, a plu- 70 rality of punches arranged in a series transverse to the path of movement of the strip, a punch actuator, individual selectors movable into and out of operative relation with said actuator and the corresponding punches, a set of permutation members operable in different combinations in response to received signals for selectively controlling the operation of said selectors. 75
10. A recording perforator comprising two groups of punches and corresponding punch 80 selectors, a separate set of controlling permutation members and a punch actuator for each group, a distributer and electro magnetic means responsive to receive definite interval code permutations for successively conditioning the sets of permutation members in different combinations, to select one punch in each group in response to each received signal, means initiated in operation by the distributer for effecting the successive operation of the punch actuators and a tape feed mechanism individual to and operated by one of said actuators. 85
11. In a telegraph receiver, a plurality of punches, individual punch selectors, tape feed mechanism, an actuator for the punches and said feed mechanism, and a set of permutation members for selectively controlling the operation of the selectors in response to received signals, one of the selectors being arranged to disable said feed mechanism. 90
12. In combination in a telegraph system, a tape controlled transmitter, a tape perforating receiver having a series of punches, said transmitter and receiver having tape feed mechanisms and corresponding series of signal and punch controlling selectors respectively, and means controlled by certain corresponding transmitter and receiver selectors for disabling said feed mechanisms. 95
13. A telegraphic tape recorder having means for selectively punching a definite number of holes disposed in a row across the tape in response to each ordinary signal and means for punching an additional hole in a previously formed row in response to a special signal. 100
14. In a telegraphic tape recorder, a step-by-step tape feed mechanism, a series of punches disposed transversely of the path of the tape, and a special punch one step in advance of the others, corresponding punch selectors, an actuator for operating the selected punches and said feed mechanism, and means for disabling said feed mechanism controlled by the special punch selector. 105
15. In a selecting telegraph, a series of transmitting selectors adapted to be controlled by a tape having transverse rows of holes, corresponding series of receiving selectors and punches controlled thereby for reproducing the transmitter controlling tape, transmitter and receiver tape feeders and means for normally operating said feeders at the end of each signal period, one each of said 110 115 120 125 130

series of selectors being arranged to disable said feed mechanism during certain special signal periods.

16. In selecting telegraphs for controlling telegraphic machines, a tape controlled transmitter having a series of signal controlling 5 selectors disposed transversely of the path of the tape and normally selectively positioned during the successive periods by cross rows of perforations of the tape, a tape feeder, and means normally operative at the end of each signal period for actuating said tape feeder, one of said selectors being arranged to disable said tape feeder to permit the selectors 10 positioned by each of certain transverse rows of the tape to control the transmitted signals during two successive signal periods.

17. In selecting telegrams for controlling telegraphic machines, a tape controlled transmitter having a series of signal controlling 20 selectors disposed transversely of the path of the tape and normally selectively positioned during the successive periods by cross rows of perforations of the tape, and a perforating receiver having corresponding series of punches and punch selectors normally selectively controlled to form a transverse row of holes on a record tape during each signal period, tape feeders for the sending 25 and receiving tapes, and means for normally operating said feeders at the end of each signal period, a special one of the selectors of each series being arranged to disable said feeders, whereby the transmitter selectors 30 are controlled by and the receiver punches form a single row of tape holes during two successive signal periods.

18. In a telegraph system, the method of sending and recording signals according to a 40 code comprising a relatively large number of components, which consists in translating and transmitting each of such signals in a compound signal of a different, definite interval code comprising a substantially smaller number of units or components and having each of said compound signals formed of 45 separate portions corresponding respectively to the components of the original signal, and translating the transmitted signals into the original code and recording the same.

19. In a telegraph system for reproducing a perforated record strip having a plurality of groups of hole positions extending transversely of the strip and transverse rows of 55 holes each comprising one hole in each of such groups, means for transmitting, under control of the tape, a plurality of definite interval code permutations, one for each of the holes in the corresponding row, during each 60 signal period, and a receiving perforator having a corresponding number of groups of punches and sets of permutation members for selectively controlling the operation of one punch in each group in response to the 65 corresponding permutations of each signal.

20. In a telegraph system for reproducing a perforated record strip having two groups of hole positions extending transversely of the strip and transverse rows of holes, each row formed of one hole in each of said groups, a transmitter and a receiving perforator each having two sets of permutation members, means controlled by the tape for selectively positioning the sets of transmitting permutation members in different combinations, and two groups of recording devices controlled respectively by two sets of receiving permutation members.

21. In a telegraph system, the method of sending and recording signals formed in accordance with a code comprising a relatively large number of components which consists in translating and transmitting each such signals in compound signals of another code comprising a substantially smaller number of components and having each compound signal formed of separate portions corresponding respectively to the components of the original signal, and translating the received signals into the original code and recording the same.

22. In a telegraph system, a plurality of groups of transmitting selectors, means common to said groups of selectors for conditioning the same in different combinations to select combinations of code impulses, common distributor means for successively imparting the selected impulses to the line, corresponding groups of receiving selectors, a common distributor means and cooperating electro-magnetic means for setting the receiving selectors in response to the received signals and a recorder common to and controlled by said groups of receiving selectors.

23. In combination in a telegraph system, a transmitter comprising a plurality of groups of selectors and common means for conditioning said groups of selectors in different combinations, a receiving recorder comprising corresponding groups of 105 selectors and actuating and record feeding mechanism common to said groups, and a common distributor and associated electro-magnetic means for conditioning the receiver 110 selectors in response to the received signals, said distributor being arranged to control the operation of said actuating and record feeding mechanism.

24. The method of code transposing which consists in assigning to each element of a signal of a code comprising a large number of elements a separate combination of elements of a signal code comprising a substantially smaller number of elements, transmitting said separate code combinations and thereafter translating the same into the ordinary code signal and recording the same.

25. In a telegraph system, means to transmit a series of groups of signals, means for perforating a strip of material in a trans-

165

35

43

53

100

105

110

115

125

130

verse line according to one of said groups of signals, and means to provide in any transverse line, an extra perforation under the control of another group of signals.

26. In a telegraph system, means to transmit a series of groups of signals, means for perforating a strip of material in a transverse line according to one of said groups of signals, and means to add to any transverse line an extra perforation under the control of a succeeding signal.

27. In a telegraph system, a tape having transverse lines of perforations, means to control the transmission of a complete code signal by a single perforation in one location in a transverse line, and means to send varying code signals according to the remaining perforations in said transverse line.

28. In a telegraph system, a transmitting distributor, means to transmit a series of code signals, a tape containing groups of transverse perforations, certain groups adapted to control the signal during a single cycle of operation of said distributor, and certain of said groups of perforations being adapted to control the signals transmitted during two cycles of operation of said distributor.

29. In a telegraph system, means to transmit a succession of permutation code signals, means for forming perforations in a strip of material according to said permutation signals, means to normally feed the strip forward after each complete perforating operation, and means controlled by certain signals to disable said feeding means.

30. In a telegraph system, means to transmit a succession of permutation code signals, means for forming perforations in a strip of material according to said permutation signals, means to normally feed the strip forward after each perforation operation, and means controlled by a certain signal to make an additional perforation, said perforation associated with the perforations made by certain of said other signals to render said certain other signals complete.

31. In a telegraph system, an automatic transmitter, perforated tape to control said transmitter, groups of perforations in said tape, means normally operative to control the transmission of a permutation code signal by each group and means controlled by certain groups to send two permutation code signals.

32. In a telegraph system, a tape having a series of transverse lines of perforations, a distributor, means to transmit during a complete cycle of said distributor a signal controlled by a single perforation in a line, and means to transmit during another complete cycle of said distributor a signal controlled by all the remaining perforations in such line.

33. In a telegraph system, a receiving device, a tape having groups of perforations disposed in transverse line, means to transmit

signals varying according to the perforations in a group, a special perforation associated with certain groups, means to transmit under the control of said special perforations an invariable signal similar in character to said varying signals, and means controlled by said special signal to change the response of the receiving device.

34. In a telegraphic tape recorder, means for forming a single transverse row of perforations in the tape one at a time and in response respectively to successive code combinations of signal elements, a step-by-step tape feeder, and means for operating the same upon the formation of each complete transverse row of perforations.
